2 SHEETS—SHEET 2.

UNITED STATES PATENT OFFICE.

DAVID McMICKEN TONER, OF BEECHWOOD, PENNSYLVANIA.

HEADLIGHT.

No. 864,439.

Specification of Letters Patent.

Patented Aug. 27, 1907.

Application filed November 28, 1906. Serial No. 345,496.

To all whom it may concern:

Be it known that I, DAVID McMICKEN TONER, a citizen of the United States, residing at Beechwood, in the county of Cameron and State of Pennsylvania, have invented a new and useful Improvement in Headlights, of which the following is a specification.

This invention relates to headlights and more particularly to headlights for locomotives; the object being to provide a headlight so constructed that the beam of light from the lamp on the reflector will be held on the track automatically while the locomotive is rounding a curve, and at the same time the lamp will be held perfectly horizontal, so that it will not be deflected when the road is rough.

Another object of my invention is to provide a reflector which can be readily attached to the ordinary head-light now in general use.

Another object of my invention is to provide very novel means for preventing the pendulum weight from shifting suddenly so as to prevent the platform carrying the lamp from being jerked or jolted.

With these objects in view, the invention consists in the novel features of construction, combination and arrangement of parts hereinafter fully described and pointed out in the claims.

In the drawings forming a part of this specification:—Figure 1 is a longitudinal vertical sectional view through my improved headlight a part being broken away. Fig. 2 is a transverse vertical sectional view of the headlight. Fig. 3 is a top plan view of the platform of the headlight removed. Fig. 4 is a perspective view of the arm carrying the pendulum and a portion of the piston rod. Fig. 5 is a detail perspective view of a portion of the lower platform showing the stud and journal block. Fig. 6 is a similar view of the top platform and journal block stud showing the manner of supporting the journal block. Fig. 7 is a perspective view of the arm and a portion of the platform supporting links. Fig. 8 is a sectional view through the platform. Fig. 9 is a vertical section through one of the cylinders.

In the drawings A indicates the casing of the headlight which is of the ordinary shape and construction, and is provided with the usual glass covered front door A'.

Arranged in the rear of the casing adjacent each side are uprights B connected together at their upper ends by a cross bar B' in which is centrally secured a forwardly projecting bolt C on which is mounted the centrally apertured T-shaped arm D, on the depending stem D' of which is mounted the inverted V-shaped perpendicular weight E. The ends of the arm D carry bolts D², on which are pivotally mounted the apertured ends of the piston rods F having piston-heads F' at their lower ends provided with openings F² which work in cylinders G adapted to be filled with alcohol

provided with oppositely disposed outwardly projecting lugs G' adjacent their lower ends which are mounted in apertures formed in the uprights B and uprights H arranged in the casing in alinement with the uprights B.

60

Mounted on the bolt C is the centrally apertured cross-arm I which is provided with a depending stem I' having a bifurcated end I² adapted to fit over a screw-bolt E² secured in the front face of the pendulum so as to swing the arm I with the arm D. The ends of the arm I carry bolts I³ on which the apertured ends J' of the links J are pivotally mounted, the lower ends of which are connected to eyes J² secured in the platform K adjacent its rear edge, so that the platform will be tilted when the weight swings, so as 70 to hold it perfectly horizontal. A stud pin K' projects out centrally from the front edge of the platform K and is mounted in a journal block L provided with a bolt L' which is pivotally mounted in the bottom of the casing. A forked arm K² projects out centrally 75 from the rear of the platform in which the depending pin E³ of the pendulum is adapted to fit so that when the pendulum swings, the platform will be carried with it. A circular grooved track K³, is secured on the top of the platform K in which are arranged balls 80 K⁴ on which is mounted the grooved circular track M' of the lamp supporting platform M, the two being pivotally connected together centrally by a pivot-bolt N. Projecting out centrally from the platform M is a stud-pin M² mounted in a journal-block O provided with a bolt O' which is pivotally mounted in a cross-bar P secured to the sides of the casing. A reflector Q is mounted on brackets Q' secured on the platform M under which a lamp is adapted to be arranged.

90

The operation is as follows:—As soon as the locomotive reaches a curve in the road-bed, it of course being understood that the inner rail is lower than the outer rail, its center of gravity is shifted from the center of the road-bed towards the inner rail causing the 95 pendulum to also seek the center of gravity which will swing the arm D causing the piston to work through the alcohol in the cylinder which will gradually allow the pendulum to reach the center of gravity without any sudden jolt, at the same time the arm I is swung 100 by the bolt carried by the pendulum working in the bifurcated stem raising the platform K into a horizontal position. When the pendulum swings over the pin in the bottom working in the bifurcated arm of the platform K, causing the platform K to turn in the 105 direction as shown by the arrows V, shifting the centrally pivoted part of the platform to W and causes the platform M to turn in a reverse direction as shown by the arrow X thereby causing the beam of light to follow the track as the locomotive rounds a curve. 110

Having thus described my invention, what I claim as new and desire to secure by Letters Patent is:—

1. In a headlight, the combination with a casing, of a pair of platforms, pivoted together, pivotally mounted in 5 swivel-blocks at opposite ends in said casing and means for oscillating said platforms in opposite directions for the purpose described. 80
2. In a headlight, the combination with a casing, of a pair of platforms pivoted together pivotally mounted in 10 swiveled journal-blocks at opposite ends in the casing, and means for tilting and oscillating said platforms for the purpose described. 85
3. In a headlight, the combination with a casing, of a pair of platforms pivoted together pivotally mounted in 15 swiveled journal-blocks at opposite ends of the casing, a pivoted arm carrying links supporting said platforms and means for rocking said arm and oscillating said platform, in opposite directions for the purpose described. 90
4. In a headlight, the combination with a casing, of a pair of platforms mounted in said casing pivoted together centrally, and a pendulum mounted in said casing for oscillating said platforms in opposite directions for the purpose described. 95
5. In a headlight, the combination with a casing, of a pair of platforms pivoted together centrally mounted in 20 said casing, and means for tilting and oscillating said platforms, for the purpose described. 100
6. In a headlight, the combination with a casing, of platforms pivoted centrally together one above the other 25 loosely mounted in said casing, and means for tilting said platforms, and oscillating them in opposite directions at the same time, for the purpose described. 105
7. In a headlight, the combination with a casing provided with a cross-bar carrying a bolt, of arms mounted on 30 said bolts supporting a pair of platforms pivoted together centrally and means for operating said arms, and platforms, for the purpose described. 110
8. In a headlight, the combination with a casing provided with a cross bar carrying a bolt, arms mounted on 35 said bolt supporting a pair of platforms pivoted together and a pendulum carried by one of said arms for swinging said arms and oscillating said platforms, for the purpose described. 115
9. In a headlight, the combination with a casing, of a pair of arms pivotally mounted in said casing, a platform supported by one of said arms having a lamp supporting 40 platform mounted thereon and a weight carried by the other arm for swinging said arms and oscillating said platform, for the purpose described. 120
10. In a headlight, the combination with a casing, of arms mounted in said casing, a platform supported by one of said arms, a pendulum carried by the other arm and a platform mounted on said platform adapted to be oscillated by said pendulum for the purpose described. 125
11. In a headlight, the combination with a casing, of an arm mounted in said casing carrying supporting links, a platform connected to said links pivotally mounted in the casing at its front edge, a platform pivotally mounted on 45 said platform pivotally mounted in the casing at its rear edge and a pendulum mounted in said casing for operating said arms and platforms, for the purpose described. 130
12. In a headlight, the combination with a casing, of a platform arranged in said casing having an outwardly projecting stud-pin mounted in a swivel-journal block, an arm mounted in said casing connected to said platform by 50 links, a platform pivotally mounted on said platform provided with a stud-pin mounted in a swiveled journal-block and a pendulum mounted in said casing adapted to operate said arm and platforms for the purpose described. 135
13. In a headlight, the combination with a casing, of a platform arranged in said casing mounted in a swiveled journal-block at its forward end and supported by links carried by an arm at its rear end, a lamp supporting platform 55 pivotally mounted on said platform mounted in a swiveled journal block at its rear end, a forked arm projecting out 75 from the rear end of the platform and a pendulum mounted in said casing, provided with a pin adapted to work in said forked arm and provided with a bolt adapted to work in the bifurcated end of the depending stem of the arm, for the purpose described. 140
14. In a headlight, the combination with a casing provided with a swiveled journal-block in its bottom, of a platform provided with a stud-pin mounted in said journal-block, an arm mounted in said casing carrying links supporting the rear end of said platform, a platform pivotally mounted on said platform provided with a stud-pin mounted in a swiveled journal block and means for operating said arms and oscillating said platforms, for the purpose described. 145
15. In a headlight, the combination with a casing, of a T-shaped arm mounted in said casing carrying piston-rods in its ends working in cylinders, a pendulum weight mounted on the stem of said arm provided with a bolt, an arm mounted in said casing provided with a depending bifurcated stem working over said bolt of the pendulum, links carried by the ends of said arms supporting a platform pivotally mounted in the casing at its front edge, a platform pivotally mounted on said platform, pivotally mounted in the casing at its rear edge, a forked arm extending out from the rear of the lower platform and a depending pin carried by the pendulum working in said forked arm, for the purpose described. 150
16. In a headlight, the combination with a casing, of a pair of platforms pivoted together, pivotally mounted in swiveled journal-blocks at opposite ends, an arm mounted in said casing carrying links connected to the rear of the lower platform, a T-arm mounted in said casing provided with piston-rods at its ends, piston heads carried by said rods provided with openings working in cylinders pivotally mounted in the casing, a pendulum weight carried by the stem of the T-arm provided with a bolt, a depending stem provided with a bifurcated end carried by the arm working over said bolt and a depending pin carried by said weight working in a forked arm of the lower platform, for the purpose described. 155
17. In a headlight, the combination with a casing, of a pair of platforms pivoted together, pivotally mounted in swiveled journal-blocks at opposite ends, an arm mounted in said casing carrying links connected to the lower platform and means for operating said arms and oscillating said platforms in opposite directions, for the purpose described. 160
18. In a headlight, the combination with a casing, of a pair of platforms pivotally connected together, pivotally mounted in swivel journaled blocks at opposite ends, an arm carrying links connected to the lower platform, provided with a depending bifurcated stem, a T-arm mounted in said casing carrying a weight on its depending stem provided with a bolt working in the bifurcated stem of said arm; and a pin carried by said weight working in a forked arm, carried by the lower platform for the purpose described. 165
19. In a headlight, the combination with a casing, of a platform provided with a stud-pin mounted in a swiveled journal-block at its front end and supported at its rear by links carried by a pivoted arm provided with a bifurcated stem, a lamp supporting platform pivotally mounted on said platform, provided with a stud pin mounted in a swiveled journal-block at its rear end, a T-shaped arm pivotally mounted in said casing carrying a weight on its stem provided with a bolt working in the bifurcated stem of the other arm, piston-rods carried by the ends of the T-shaped arm provided with piston heads having openings formed therein adapted to work in pivotally mounted cylinders containing liquid and a depending pin formed on the weight adapted to work in a forked arm projecting out from the lower platform, for the purpose described. 170
